UNITED STATES PATENT OFFICE.

ORLANDO KLING, OF IDAHO SPRINGS, COLORADO.

DESIGN FOR A WATCH AND CLOCK DIAL.

SPECIFICATION forming part of Design No. 16,045, dated April 14, 1885.

Application filed March 7, 1885. Term of patent 14 years.

To all whom it may concern:

Be it known that I, ORLANDO KLING, of Idaho Springs, Clear Creek county, Colorado, have invented and produced a new and original Design for a Watch and Clock Dial, of which the following is a full, clear, and exact description.

The leading feature of my design consists of the configurated series of triangles intermediate of concentric circles, and of the series of lesser triangles in the points of the aforesaid series of triangles.

Reference is to be had to the accompanying drawing, forming a part of this specification, in which a face view of my new design for a watch or clock dial is represented.

The dial A has two concentric circles, B and C, the latter being divided into sixty equal parts and the former into twenty-four parts, centrally within each of which latter parts subdivision marks D are arranged. Between the circles B and C are twelve triangles, E, the bases be-

ing on the circle C and the apices on the circle B. In the outer parts or points of the triangles E black or colored pointed triangles F are produced, so that the several triangles E may be more readily distinguished.

Having thus described my invention, I claim as new and desire to secure by Letters Patent—

1. The design for dials herein shown and described, the same consisting of the configurated series of triangles arranged intermediate of two concentric circles.

2. The herein described and shown design for dials, the same consisting of two concentric circles, twelve triangles between the circles, and triangles at the points or apices of the triangles, between the ends, substantially as set forth.

ORLANDO KLING.
